[57] **CLAIM**

The ornamental design for spiral chute, as shown and described.

DESCRIPTION

FIG. 1 is a front elevational view of a spiral chute showing our new design;

FIG. 2 is a side elevational view thereof; and

FIG. 3 is a top plan view thereof.

A portion of the spiral chute is shown broken away to indicate indeterminate length.

FIG. 1.

FIG. 2.

FIG. 3.
